UNITED STATES PATENT OFFICE.

MICHAEL RILEY, OF LONDON, OHIO.

FOOT-GUARD FOR RAILWAY-FROGS.

SPECIFICATION forming part of Letters Patent No. 530,658, dated December 11, 1894.

Application filed August 11, 1893. Serial No. 482,903. (No model.)

To all whom it may concern:

Be it known that I, MICHAEL RILEY, a citizen of the United States, residing at London, in the county of Madison and State of Ohio, have invented a certain new and useful Improvement in Foot-Guards for Railway-Frogs, of which the following is a specification.

My invention relates to the improvement of filling plates for the angles of railway frogs and the objects of my invention are to provide simple, reliable and effective filling plates for the angular space between the converging frog rails; to so construct said device as to prevent its interference with the usual nuts and bolts of the fish plates and to otherwise produce a durable and neat filling plate for frogs which will operate to prevent the catching of the feet in the frog angles and to produce other improvements which will be more specifically pointed out hereinafter. These objects I accomplish in the manner illustrated in the accompanying drawings, in which—

Figure 1 is a plan view of a railway frog having my filling plates therein. Fig. 2 is an enlarged transverse section on line $x-x$ of Fig. 1. Fig. 3 is a view in perspective of one of said filling plates showing the same inverted and Fig. 4 is a transverse section of the converging frog rails showing a modification in the manner of securing the filling plate in position.

Similar letters refer to similar parts throughout the several views.

35 a and b represent the converging main and side track or switch rails which form the usual frog point c , and a' b' represent the broken continuations of said rails which also converge toward said frog point in the usual manner. 40 The convergence of the above rails results in the formation between the same of the angular spaces indicated in the drawings, which said spaces are adapted to be filled as herein-after described by my improved filling plates.

45 d represents one of my improved filling plates the body of which is substantially in the form of an isosceles triangle. The plate body thus formed has its longer sides flanged downward slightly, said side flanges being indicated at d' , while the ends of said plate body are bent downward as indicated respectively at e and e' to a greater depth than said

side flanges. The plate thus formed is adapted as shown in the drawings to fit snugly within the angular space formed by the converging 55 rails, the truncated smaller ends of said plates preferably extending within a short distance of the apex of said angular spaces although it is evident that the entire space might be filled up to the point or apex thereof by so 60 forming said plates.

As indicated in the drawings the plates d are normally supported below the upper surface of the rail heads and said side flanges b' of the plates are inclined inward slightly to 65 conform to the incline or bevel of the rail tread sides.

The manner of securing my improved filling plate in the above described position consists as indicated in driving spikes f down 70 through the bodies of said plates and into the ties g upon which the track rails are mounted in the usual manner. Before driving said spikes, however, I preferably surround each of the same with a coil spring h , the latter 75 bearing as shown between the under side of the plate d about the spike opening therein, and the top of the tie g . It will be observed that these springs h serve to normally operate the filling plate at such height as to prevent 80 its coming into contact with the inwardly projecting nuts and bolt ends i and i' , which are usually employed in connecting the fish-plates i^2 on opposite sides of the rails. It is 85 obvious that the angular space between the rails a' and b' may be filled in the manner prescribed for the space between the rails a and b , and that the filling plates thus employed will serve to prevent any possibility of catching a foot in the frog angle. It will 90 also be seen that the plates are supported in such position as not to present a bearing for the car wheel flanges and that in case the plates are subjected to any weight, the springs will serve to cushion said plates against a sudden 95 downward movement.

From the construction and operation of my improved frog angle filling plates, it will be seen that the same may be produced of thin sheet steel or other suitable material at a reasonable cost of manufacture and in a durable and reliable form. In case there are no convenient ties into which the attaching spikes may be driven, I may provide transverse con-

necting arms or bars *k*, the latter passing beneath the bases of the rails and having hooked shaped ends which engage with the outer sides of the rail flanges. This connecting bar *k* may 5 be provided with a central screw threaded opening through which is adapted to pass the threaded end portion of a bolt *k'*, the latter passing loosely through the filling plate and being surrounded by the coil spring *h* and 10 thus being made to serve the purpose of the spikes indicated in Fig. 2 of the drawings.

Having now fully described my invention, what I claim, and desire to secure by Letters Patent, is—

In a foot guard or filling plate for railway frogs the combination with the converging rails and ties upon which the latter are supported, of the angular filling plate *d* adapted to fit as described between said converging rails, spike holes in said plate, spikes passing 20 loosely therethrough and into said ties and springs between said plates and ties, substantially as and for the purpose specified.

MICHAEL RILEY.
